UNITED STATES PATENT OFFICE

153,375

DESIGN FOR A TRAILER BODY OR SIMILAR ARTICLE

John R. Morgan, Chicago, Ill., assignor to Dunbar Kapple, Inc., Geneva, Ill., a corporation of Illinois

Application September 19, 1947, Serial No. 141,476

Term of patent 7 years

(Cl. D14—3)

To all whom it may concern:

Be it known that I, John R. Morgan, a citizen of the United States and a resident of Chicago, in the county of Cook and State of Illinois, have invented a new, original, and ornamental Design for a Trailer Body or Similar Article, of which the following is a specification, reference being had to the accompanying drawing, forming a part thereof.

Fig. 1 is a side elevational view of a trailer body or similar article, showing my new design.

Fig. 2 is a top plan view of the same.

Fig. 3 is a front elevational view of the same.

Fig. 4 is a rear elevational view of the same. Both sides of said trailer body are alike.

I claim:

The ornamental design for a trailer body or similar article, substantially as shown and described.

JOHN R. MORGAN.
